(57) **CLAIM**

An ornamental design for a hemodynamic recording system signal input box with smart mount, as shown and described.

DESCRIPTION

FIG. 1 is a top perspective view of a hemodynamic recording system signal input box with smart mount in accordance with the design;

FIG. 2 is a right side view thereof;

FIG. 3 is a left side view thereof;

FIG. 4 is a top view thereof;

FIG. 5 is a bottom view thereof;

FIG. 6 is a front side view thereof;

FIG. 7 is a rear side view thereof; and,

FIG. 8 is a bottom perspective view thereof.
